CALKING AND CENTERING MEANS

Richard J. Gollong, Johnson City, Tenn., assignor to American Glanzstoff Corporation, New York, N. Y., a Corporation of Delaware

Application December 16, 1931
Serial No. 581,496

2 Claims. (Cl. 8—18)

My present invention relates to a new type of gasket or fitting adapted primarily for use in a washing or treating apparatus.

In the manufacture of artificial threads or filaments and the like by the viscose process the threads or filaments are wound on perforated or foraminated bobbins or spools and are then subjected to a liquid treatment. This treatment is accomplished by passing liquids through the body of the threads or filaments by the application of pressure or vacuum. The bobbins or spools are arranged in stacks in a tank, each stack fitting over an opening in the bottom of the tank and the treating liquid is forced through the opening into the interior of the bobbin or spools; through the openings formed therein, through the yarn body and thence into the tank. When a vacuum system is used the flow of the liquid is in the reverse direction.

One object of my present invention is to provide a suitable means for centering the bobbins or spools over the openings in the tank.

Another object of my invention is to provide a new arrangement for centering and calking the stacks of bobbins or spools so that the loss of pressure or vacuum will be reduced to a minimum.

A further object of my invention is to provide a suitable centering and calking arrangement which may be easily assembled and disassembled and which functions more efficiently than those now in use.

These and other objects will become more apparent from a study of the following description and the drawing in which:

Fig. 1 is a sectional view of my device;

Fig. 2 is a top plan view of the gasket;

Fig. 3 is a sectional view of the gasket taken along the lines 3—3 of Figure 2; and

Fig. 4 is a sectional view of the tube forming part of the device.

Referring now more particularly to the drawing I have shown in detail a preferred embodiment of my invention. My device consists essentially of a two part centering and calking arrangement and comprises a tube —10— made of a heat and acid resistant material. The tube is substantially cylindrical in shape and is provided at one end with a flange —11— having a beveled or inclined portion —12—. As is clearly shown in Fig. 4 the tube is provided with a threaded portion —13— which is spaced from the flange leaving a smooth surface —14—. The lower end of the tube is cut away to form a shoulder —15— leaving a smooth neck like portion

—16— adapted to receive a tube or hosing connecting the device to a vacuum or pressure system.

The gasket comprises a circular member —17— having a central opening —18— formed therein. The inner wall thereof is cut as shown at —19— forming a shoulder —20—. The shape of this cut-away portion corresponds to the shape of the flange of the tube and the shoulder —20— fits snugly against the smooth portion —14— formed on the tube. The gasket may be made of soft rubber or other suitable material.

The top of the gasket is provided with a plurality of radially disposed grooves or slots —21— which communicate with the central opening. By this construction all of the water or treating liquids will be drained towards the center of the device. To facilitate this draining the tube itself is formed with a countersunk portion —22—.

In assembling the device the flanged end of the tube is fitted in the cut-away portion formed in the gasket as is clearly shown in Fig. 1. The tube is then passed through the opening —23— formed in the tank —24— and is secured thereto by means of a suitable lock-nut —25— threaded on the threaded portion of the tube. The shoulder —20— is thus held firmly against the bottom of the tank forming an effective seal between the bottom of bobbin or spool placed in the gasket and the tank. The size of the gasket is such that the inner wall of the spool snugly engages the sides thereof.

From the above description it will be appreciated that I have provided a device which may readily be assembled and secured in the tank. The tube may be made of any suitable material which will withstand a temperature of at least 65° C. and the action of the acids which may be present in the treating liquids used.

With the fittings now in use, when any part thereof is injured or otherwise rendered useless, the entire fitting becomes worthless and must be discarded making such fittings very costly. By using a two part construction the gasket portion which is usually that portion of the fitting which becomes worn first, may readily be replaced thus avoiding the replacement of the entire fitting.

The provision of the drainage openings in the gasket prevents the accumulation of the treating liquid around the base of the lowermost spool preventing the deterioration of the spool and the thread at that point caused by the action of the treating liquids thereon.

While I have illustrated what I believe to be a preferred embodiment of my invention it is ob-

vious that various changes and alterations might be made in the general form of the parts described without departing from my invention and hence I do not limit myself to the precise details set forth but consider myself at liberty to make such changes and alterations as fairly fall within the spirit and scope of the appended claims.

What I claim as new is:

1. In a treating tank having an opening formed in the bottom thereof, a device for securing and centering spools over said opening comprising, in combination, a tube-like member having a flanged upper end and a threaded portion, a gasket fitting around said flanged end and having spaced drainage slots formed therein, said tube

fitting in such opening, and a lock-nut engaging said threaded portion to secure said device in place.

2. A device for securing and centering spools over an opening in a tank comprising a tube, a flange formed integrally therewith, the periphery of said flange being inclined upwardly, a gasket having a portion cut away to receive said flange and having a shoulder fitting beneath said flange, the upper portion of said gasket being provided with drainage slots, said tube being provided with means whereby the tube may be held in position in the opening in said tank.
